(57) **CLAIM**

The ornamental design for an electronic cable with an adapter, as shown and described.

DESCRIPTION

FIG. 1 is a front elevation view of an electronic cable with an adapter showing our new design;

FIG. 2 is a rear elevation view thereof;

FIG. 3 is a left side elevation view thereof;

FIG. 4 is a right side elevation view thereof;

FIG. 5 is a top plan view thereof;

FIG. 6 is a bottom plan view thereof;

FIG. 7 is a front of a Mini Display Port showing my new design; and,

FIG. 2 is a front elevation view thereof, with the top portion exploded.

The broken line in the figure drawings is included for the purpose of illustrating environment and forms no part of the claimed design.
